UNITED STATES PATENT OFFICE.

CHARLEY D. OLAND, OF CENTRALIA, ILLINOIS.

EMERGENCY-WHEEL SKID.

1,375,063.

Specification of Letters Patent. Patented Apr. 19, 1921.

Application filed August 13, 1919. Serial No. 317,173.

To all whom it may concern:

Be it known that I, CHARLEY D. OLAND, a citizen of the United States, residing at Centralia, in the county of Marion, State of Illinois, have invented certain new and useful Improvements in Emergency-Wheel Skids; and I do hereby declare the following to be a full, clear, and exact description of the invention, such as will enable others skilled in the art to which it appertains to make and use the same.

This invention relates to skids such as are employed in railroad yards. In the shifting of cars in the making up of trains, the cars are successively cut loose under way at the hump, beyond which they gravitate to their respective positions and which gravitation is controlled by the hand brakes. It frequently happens that the brakes fail to work, and when this occurs, there is a wreck not only of the car in motion, but of one or more of the cars of the train that is in the making.

It is the object of the present invention to provide skids that may be readily placed upon the track in advance of the runaway car, by an attendant provided for that purpose, and which by reason of its particular construction, will stop the car within a short distance and without injury to it.

Further objects of the invention have to do with the provision of means for properly distributing weight, means for automatically sanding the track in advance of the skid and means for causing the skid to ride over inequalities at the rail joints, which in yards are not so carefully maintained as upon the road.

Other objects and advantages of the invention, will be understood from the following description.

In the drawings,

Figure 1 is a perspective view showing a skid embodying the present invention.

Fig. 2 is a section taken longitudinally and vertically through a skid embodying the present invention, the sander operating rod being in elevation at its body portion and the position of the tread of a wheel being indicated in dotted lines.

Fig. 3 is a rear perspective view of the sand box removed from the skid and showing the construction and arrangement of the

closure for the discharge opening, and its actuating rod.

Fig. 4 is a front end view of the skid.

Referring now to the drawings, there is shown a skid comprising a body 5, from which extends the tail 6, designed to rest, with the adjacent portion of the body, upon the tread surface of a railroad rail.

The body 5 of the skid is hollow and its forward end is open, as illustrated, the opening extending through the adjacent end portion of the bottom of the head, for a purpose to be presently explained.

To prevent lateral movement of the skid from the rail, while permitting sliding movement longitudinally of it, there are provided flanges 7 and 8 that depend from the body 5 with their outer side faces forming continuations of the corresponding side faces of the body, the spacing of these flanges being slightly greater than the width of the rail upon which the skid is to be used.

In practice, the skid is disposed upon the rail with the free end portion of its tail in the direction of the approaching car, and the upper surface of the tail being beveled, as shown at 9, the car wheel will readily run up the bevel and onto the skid. Beyond the bevel the upper surface of the skid is curvingly concaved, as shown at 10, the curve being the arc of a circle extending from the top of the bevel, to the upper surface of the body 5 substantially midway of the length of the latter, and this curvature has a radius somewhat less than that of the car wheel, so that pressure of the wheel will be upon the skid at widely separated points to distribute the pressure throughout the rail-contacting portion of the skid with substantially uniform friction upon the rail.

From the foregoing description it will be understood that a skid is disposed upon either or both rails, and that when active, they slide along the rails, and by friction thereon, stop the progress of the car.

It will be noted that the forward end of the bottom of the body 5 is beveled at its underside, as shown at 9', and when the skid encounters a minor obstruction, such as the slight upward displacement of a rail end, this bevel strikes the obstruction and guides the skid over it.

It will be noted that the flanges depend below the bottom of the body somewhat more than the height of the bevel and so as to provide against lateral displacement 5 of the skid from the rail even when the skid is raised over the obstruction.

To provide against lodgment of the skid against an end rail projecting upwardly a distance greater than the height of the 10 bevel, a roller 11 is mounted upon a pin 12 transversely of the body of the skid, within its forward end portion, the lowermost portion of this roller being slightly below the upper end of the bevel 9'. It will of course 15 be understood that when this roller 11 strikes a rail end, it rotates and lifts the skid so that its bevel 9' will strike the rail end and further lift the skid onto it.

To provide for sanding the rail, a sand 20 box 13 is disposed within the hollow body above and rearwardly of the roller 11, the box having a discharge spout 14 that depends behind the roller and terminates slightly above the bottom of the chamber 15 25 of the body and in advance of the bottom so that it may discharge sand onto the rail between the roller and the bevel 9'.

The spout 14 is normally closed by a U 30 shaped closure plate that includes a bight portion 16 extending throughout the width of the discharge opening of the spout, and upwardly directed side portions 17 that pivotally engage the stub shafts 18 respectively that project laterally from the lower converged portions 19 of the ends of the spout. 35

In order that the closure plate may be automatically swung from closing position and permit of a feed of sand immediately upon engagement of a car wheel upon the 40 skid, there is provided an actuating rod 20 that passes slidably through an opening 21 in the rear wall of the chamber 15. The outer end of this rod 20 extends slightly beyond the face of the concavity 10 while its inner end is yoked, the arms 22 of the yoke being pivoted respectively to the upper end portions of the arms 17 of the U shaped closure plate, above the shafts 18. With this construction it will be seen that when 45 the car wheel enters upon the skid, it strikes the outer end of the rod 20 and forces it inwardly, causing the closure plate of the sand box to swing to open position and permit of discharge of sand onto the rail. The 50 rod 20 is held normally and yieldably in position to hold the closure plate active, by means of a helical spring 23 that is disposed in the countersunk outer end portion 24 of the opening 21 and bears at one end 55 against the bottom of the counter sink, with its other end against a pin 25 that is passed through the rod 20.

The sand box is shown as provided with a hinged closure 26 at its forward end and 60 a spring finger 27 that bears against the

closure 26 and holds it normally active, provision being thus made for readily supplying sand to the box. The box is held in position in the desired manner, such as by means of a pin 28 passed through it and the sides of the body 5 of the skid, the pin being removable to permit of removal of the box when desired. 70

A handle 29 is provided upon the body of the skid to facilitate manipulation of it. 75

What is claimed is:

1. A skid of the class described including a rail engaging portion having rail supporting portions on its upper face spaced longitudinally of the rail engaging portion and disposed to hold the tread of a wheel free from the portion of the skid therebetween. 80

2. A skid of the class described including a rail engaging portion having wheel supporting portions spaced longitudinally of its upper face and disposed to hold the tread of a wheel free from the portion of the skid therebetween, the skid at one end having its upper face beveled from that extremity of the skid to the corresponding wheel supporting portion. 85

3. A skid of the class described having a sanding device and means operable by a wheel upon the skid for rendering the sanding device active. 95

4. A skid of the class described having a sanding device provided with a discharge opening and a normally closed closure, and means operable by a wheel upon the skid for shifting the closure to open position. 100

5. A skid of the class described having the forward end of its lower face beveled and a transverse roller disposed in advance of the bevel with its lowermost portion touching a plane between the upper and lower ends of the bevel, the skid having laterally spaced longitudinal flanges which depend below the bottom face of the skid a distance greater than the height of the bevel, whereby to prevent lateral displacement of the skid from a rail when raised under the influence of the bevel. 110

6. A skid of the class described having a transverse roller disposed at its forward end and above and forward of the rail-tread 115 engaging bottom face of the skid, the skid having laterally displaced longitudinal flanges depending below its bottom.

7. A skid of the class described comprising a hollow body open at its front end and the front portion of its bottom, and a roller disposed transversely of the body and exposed forwardly and downwardly through the corresponding open portions of the body with its lowermost portion touching a plane 125 slightly above the bottom face of the body. 120

8. A skid of the class described comprising a hollow body opening at its front end and the front portion of its bottom, a roller disposed transversely of the body and ex- 130

posed forwardly and downwardly through the corresponding open portions of the body, a sand holder within the body having a discharge spout disposed to discharge through 5 the open portion of the body in the rear of the roller, and means for controlling feed of sand from the sand box.

In testimony whereof, I affix my signature in the presence of two witnesses.
